REFRIGERATING COOLING UNIT

Russell H. Bird, Detroit, Mich.

Application February 13, 1935, Serial No. 6,329

5 Claims. (Cl. 62—101)

This invention relates to a cooling unit and is a continuation in part of my former patent application Serial No. 723,765, filed May 3, 1934.

The object of my invention is to produce a refrigerating unit especially adapted for merchandise vending machines requiring temperature regulation for preserving the various kinds of goods sold therein.

Another object is to produce a special cooling unit that will operate automatically for maintaining a constant temperature within an adjacent merchandise compartment.

A further object is to produce a refrigerating unit that will function by a liquid circulating medium, controlled by a connected thermostatic bellows valve, and without other external mechanical means.

A still further object is to produce an automatic cooling unit that is simple in construction, easily and efficiently operated, and that can be manufactured at a very low cost.

These several objects are attained in the preferred form by the construction and arrangement of parts more fully hereinafter set forth.

Similar parts on all drawings are marked by similar numerals or letters.

Fig. 1 is a vertical sectional view through a cabinet inclosure, taken just inside the back cabinet wall as indicated on the line 1—1 shown in the Fig. 2, showing the installation of my cooling unit mounted therein.

Fig. 2 is also a vertical sectional view taken through the cabinet centerline as on line 2—2 of the Fig. 1, showing the spiral cooling coil and the operating parts of the controlling thermostatic bellows valve.

Fig. 3 is an enlarged detail in cross section of the thermostatic bellows, showing the general construction thereof.

Fig. 4 is a cross sectional view through the cabinet taken on the line 4—4 of Fig. 2, but from the front of the cabinet, showing the spiral cooling coil as mounted in the top of the merchandise chamber compartment, and its connecting means to the thermostatic bellows valve.

Fig. 5 is also a cross sectional view through the cabinet cooling compartment, taken on the line 5—5 of the Fig. 2, but from the front of the cabinet, showing the liquid retainer tank, and valved tube connecting the spiral cooling coil to the liquid container tank.

Fig. 6 is a vertical sectional view through the air check valve taken on the line 6—6 of Fig. 5, showing the operating valve parts.

My device can best be understood by illustra-

tion and description together with the cabinet with which it is to be used, it being especially adapted for vending machine cabinet construction, although it may be used with any other type of cabinet having separated compartments, 5 equally as well, and while I herein illustrate my cooling unit as applied to a single merchandise compartment, it is to be understood that various cooling unit coils may be extended from the same liquid container tank and to different merchandise compartments, each being regulated to any desired temperature through the inclosed thermostatic bellows valve.

In general, my device comprises a cooling compartment positioned above a merchandise 15 compartment, preferably formed of heat insulating walls, the two compartments being separated from each other. The upper cooling compartment being suitable for retaining ice therein, and is provided with a liquid tank mounted 20 on the compartment bottom, said tank being connected with circulating cooling pipes mounted in the lower merchandise compartment, so arranged as to cause a circulation of inclosed liquid through the coils and back to the tank, 25 controlled by a connected thermostatic valve.

I will now describe more fully the detailed construction of my device, referring to the drawings and the marks thereon.

The cabinet 1 is preferably formed with a lower 30 merchandise compartment A and an upper refrigerating compartment B, said compartments being separated but made as a single complete structure. All of the cabinet walls being made of suitable heat insulating material and of 35 the ordinary refrigerator construction, preferably as illustrated in Figs. 1, 2, 4, and 5 of the drawings. The refrigerator compartment B is preferably lined with suitable rust-proof sheet lining *a*, and is provided with a thin sheet metal 40 liquid container tank 2, closed, fitted and mounted within the compartment bottom, the liquid tank preferably being made of aluminum alloy, or other metal having high heat conductivity. It is desirable to have the refrigerator compartment 45 bottom formed of a separated insulated wall section 3, beveled and fitted within the cabinet structure as indicated in Figs. 1 and 2 of the drawings, for convenience in installing, removing or replacing the cooling unit within the cabinet compartments. The bevel wall joints may be made as 50 tight and as secure as a solid structure, but affords means of displacing the assembled cooling unit without dis-assembling same. Through the bottom cabinet wall 3 is mounted a vertical out- 55

let pipe 4, extended downward into the merchandise compartment A. The upper end of the outlet pipe is mounted on the bottom of the liquid container tank and opens therein, and the lower 5 end of pipe 4 carries a cylindrical valve casing 5 mounted thereon and positioned below the merchandise compartment top wall. Within the valve casing 5 is a movable plunger 6, slidably mounted therein and provided with suitable means 10 for making it liquid tight with the casing walls, said plunger 6 also being provided with a mechanical thermostatic bellows 7 mounted therebeneath, of a size to position the plunger top slightly above the casing chamber center, said 15 thermostatic bellows being attached to both plunger and casing walls, designed to expand and contract with the temperature variations and displace the attached plunger 6 therewith. Any standard type of thermostatic bellows providing 20 substantial expansion, may be used, the exact type not being material to my invention. An enlarged detail cross-sectional view through the bellows showing its general structure is shown in Fig. 3 of the drawings, to illustrate the heat expanding element mounted therein. Connected to one side of the valve casing 5 is a circulating cooling pipe 8, formed in a spiral shape encircling the connected valve casing and opening therein above the plunger top. The coils of the spiral pipe are 25 inclined upward leading toward the outer coil end, using as many coil turns as may be necessary to secure the required pipe radiation for the merchandise compartment A in which it is to be used. The outer end of the spiral cooling coil 8 30 is positioned near the cabinet base section 3 and carries attached thereto a small liquid circulating tube 9 of a considerable reduced diameter. The tube 9 is passed through the base wall 3 and into the refrigerator compartment B to a position near 35 the chamber top, the top tube end being curved at approximately right angles and carries mounted thereon a combination air and check valve 10. An extension tube 11, of the same size of the circulating tube 9, is mounted on the opposite side 40 of the check valve 10, said tube being curved downward and connected to the liquid container tank 2 through the tank top wall, and opening therein, completing the liquid circulating line from the tank bottom through the thermostatic 45 bellows, cooling coil, through the tubes and check valve back to the tank container. The check valve 10 is provided with a small air vent hole 12 formed through the top closing cap to prevent a 50 vacuum within the system, and with the tube openings for the pipes 9 and 10 positioned directly 55 opposite each other. A small cork ball valve 13 is placed inside the valve casing, designed and positioned to engage the tube wall openings when lowered to that position, thus closing the tube 60 liquid passage, or if the ball valve be raised within the valve casing by the flow of liquid therein by the rising of the thermostatic plunger 6, the ball valve 13 may engage and close the air vent 12 in the casing top. The valve being principally 65 designed to prevent leaking of the circulating liquid should the cooling element section be removed from the cabinet, and also provides a reserve liquid chamber for any surplus liquid in the 70 circulating system should the thermostatic controlled plunger 6 be raised too high. The air vent 12 prevents vacuum within the pipe line and provides an even flow of the liquid therethrough.

In operating my refrigerating cooling unit, the liquid container tank 2 and the connected circulating pipes should be filled with a non-freeze

liquid, and to a level below the side ports 14 of the check valve 10 when the proper desired temperature within the merchandise compartment A is attained, the refrigerator compartment B being filled with ice, or dry ice. It is known that cold liquids settle toward the bottom or flow downward within the containing walls, and that the warmer liquids flow upwards toward the top of the container. The ice compartment B containing the liquid container tank 2 cools the liquid therein rapidly, the same settling within the cooling coil 8 in the adjacent merchandise compartment A, lowering the temperature in that compartment. When the temperature within the merchandise compartment A raises to a higher degree, the thermostatic bellows 7 automatically expands raising the plunger 6, and raises the liquid level within the check valve 10 causing same to overflow through the valve casing, and close or fill the circulating system and allow circulation to re-establish therein, the warm liquid from the chamber A rising through the tubes 9 and the cooled liquid within the tank 2 settling into the spiral cooling coil 8 for cooling the compartment A to the desired temperature. When the desired compartment temperature is reached, the thermostatic bellows 7 will have contracted sufficiently to have lowered the plunger 6 and circulating liquid within the check valve 10 below the valve wall ports 14, and automatically stop the circulation. The desired temperature may be regulated for the merchandise compartment A, either by mechanical adjustment as is usually provided for the thermostatic unit, or by varying the height of the circulating liquid within the check valve chamber for causing the liquid to overflow the valve ports 14 at the desired temperature, re-establishing the circulation within the cooling system.

While I have illustrated my invention by a single coil cooling unit as applied to a single compartment chamber, it is to be understood that as many coils 8 as may be desired may be extended from the same liquid container tank 2, and these coils may be placed in different chambers and regulated to different desired temperatures independently of each other through the thermostatic controlled plunger valve, each circulating system being applied to the tank 2 separately.

Having fully described my refrigerating cooling unit, what I claim as my invention and desire to secure by Letters Patent is:

1. A refrigerating unit adapted for cooling an adjacent merchandise compartment and used in combination therewith, comprising an ice chamber compartment formed of suitable heat retaining walls and mounted above the merchandise compartment, a closed liquid container mounted in the bottom of the ice compartment, a liquid outlet pipe mounted in the bottom of said liquid container and projected through the bottom compartment wall into the adjacent merchandise compartment, liquid circulating cooling pipes mounted within the merchandise compartment and connected to said outlet pipe in a manner for circulating liquid from the liquid container therethrough, a thermostatic expansion unit mounted within said liquid circulating cooling pipe passage, and in a manner to change the pipe volume capacity as the surrounding temperature is varied, and a tube mounted on the opposite end of said circulating cooling pipe for connecting same to the top side of the closed liquid container.

2. A refrigerating unit adapted for cooling an

- adjacent merchandise compartment and used in combination therewith, comprising an ice chamber compartment formed of some suitable heat resisting walls and mounted above the merchandise compartment, but separated therefrom, a closed liquid container mounted within the bottom of said ice compartment, a liquid outlet pipe mounted on the bottom side of the liquid container and projected through the bottom compartment wall into the adjacent merchandise compartment, a spiral pipe cooling coil having one end mounted on the bottom end of said outlet pipe and opening therein, a thermostatic bellows expansion unit mounted within the said spiral pipe cooling coil passage, and in a manner to change the inclosing pipe volume capacity as the surrounding temperature is varied, said spiral cooling coil having its opposite end connected by a curved tube to the top of the liquid container in a manner for circulating liquid therefrom through the connected cooling coil.
3. A refrigerating unit adapted for cooling an adjacent merchandise compartment and used in combination therewith, comprising a cooled chamber compartment formed of suitable heat insulated walls and mounted above an adjacent merchandise compartment, but separated therefrom, a closed metal liquid container mounted within the bottom of the ice compartment, a liquid outlet pipe mounted in the bottom of said liquid container, opening therein and projected through the bottom compartment wall into the adjacent merchandise compartment, a cylindrical valve chamber mounted on the bottom of said outlet pipe, a plunger slidably mounted within said cylindrical valve chamber and provided with a thermostatic bellows for actuating same, said bellows being connected to the plunger and casing end wall, a spiral pipe cooling coil having one end connected to the cylindrical valve chamber and opening therein, said coil having its opposite end connected by a curved tube to the top of the liquid container and opening therein in a manner for causing liquid circulation therethrough when the entire system is filled with a non-freezable liquid.
4. A refrigerating unit adapted for cooling an adjacent merchandise compartment and used therein with a non-freezable liquid, comprising a chilled chamber compartment formed of suitable heat insulated walls and provided with a door opening therein, said ice compartment being mounted above an adjacent merchandise compartment, but separated therefrom, a closed metal liquid container mounted within the bottom of the ice compartment completely covering the compartment bottom, an outlet pipe mounted on the bottom of said liquid container, opening therein and projected through the bottom ice compartment wall into the merchandise compartment, a cylindrical valve casing mounted on the bottom end of said outlet pipe, a plunger slidably mounted within the valve casing and provided with a thermostatic bellows for actuating same, said bellows being connected to the plunger and to the casing end, a spiral pipe cooling coil mounted within the top of the merchandise compartment and having its inner end connected to the cylindrical valve casing and opening therein above the plunger, said spiral coil being positioned with its pipe coils inclined upward leading toward the outer end thereof, said outer spiral coil end being connected by a curved tube to the top side of the liquid container, said curved tube being extended above the container top wall.
5. A refrigerating unit adapted for cooling an adjacent merchandise compartment and used therein with a non-freezable liquid, comprising a cooled chamber compartment formed of suitable heat insulating walls and provided with a door opening therein, said cooled compartment being mounted above an adjacent merchandise compartment but separated therefrom, a closed metal liquid container mounted within the cooled compartment bottom, a liquid outlet pipe mounted on the bottom of the liquid container, opening therein and projected through the bottom compartment wall into the adjacent merchandise compartment, a cylindrical valve casing mounted on the bottom of said outlet pipe, a plunger slidably mounted within the valve casing and provided with a thermostatic bellows for actuating same, a spiral pipe cooling coil mounted within the top of the merchandise compartment and having its inner end connected to the cylindrical valve casing above the inclosed plunger, and opening therein, said spiral coil being positioned with its pipe coils inclining upward toward the outer coils thereof, the outer end of said coil being connected by a curved tube to the top side of the liquid container and opening therein, said curved tube being extended above the container top and is provided with an air check valve positioned at the top of the tube curved section, designed to circulate liquid therethrough at certain temperatures when the liquid container and pipes are filled with a non-freeze liquid.
